US00D941051S

(12) **United States Design Patent** (10) Patent No.: **US D941,051 S**
(45) Date of Patent: **** Jan. 18, 2022**

(54) **SHOWER HANGER**

(71) Applicant: **The Procter & Gamble Company**,
Cincinnati, OH (US)

(72) Inventors: **Douglas Charles Cook**, South
Lebanon, OH (US); **Shaun Shang-Yun
Chan**, Montgomery, OH (US); **Scott
David Hochberg**, Cincinnati, OH (US);
Christopher Raymond Lo, Cincinnati,
OH (US); **Nicole Alisa Renee Lockett
Turner**, Fairfield, OH (US); **Marilyn
Anne Vennemeyer**, Cincinnati, OH
(US); **Sharonda Lee Crawford
Washington**, Cincinnati, OH (US)

(73) Assignee: **The Procter and Gamble Company**,
Cincinnati, OH (US)

(**) Term: **15 Years**

(21) Appl. No.: **29/728,688**

(22) Filed: **Mar. 20, 2020**

(51) LOC (13) Cl. **23-02**

(52) U.S. Cl.

USPC **D6/525**; D6/553
(58) **Field of Classification Search**
USPC D6/525, 532, 432, 531, 553, 555, 559,

CLAIM

The ornamental design for a shower hanger, as shown and described.

DESCRIPTION

FIG. 1 is a first perspective view of a shower hanger, embodying our new design;

FIG. 2 is a front view of the shower hanger of FIG. 1; FIG. 3 is a first side view of the shower hanger of FIG. 1; FIG. 4 is a back view of the shower hanger of FIG. 1; FIG. 5 is a second side view of the shower hanger of FIG. 1;

FIG. 6 is a top view of the shower hanger of FIG. 1; and, FIG. 7 is a bottom view of the shower hanger of FIG. 1. Broken lines are used to illustrate portions of the shower hanger or environmental subject matter that form no part of the claimed design. None of the broken lines form any part of the claimed design.
